AUGUST HUND, OF BETHESDA, MARYLAND, ASSIGNOR, BY MESNE ASSIGNMENTS, TO
FEDERAL TELEGRAPH COMPANY, A CORPORATION OF CALIFORNIA

PIEZO-ELECTRIC CRYSTAL CONTROL SYSTEM

Application filed May 12, 1927. Serial No. 190,884.

My invention relates broadly to piezo electric controlled oscillator circuits, and more particularly to a piezo electric crystal controlled oscillator system having means for stabilizing the operation of the oscillation system and preventing reactionary effects upon the piezo electric crystal element.

One of the objects of my invention is to provide a piezo electric crystal oscillator system with a branch circuit connected therewith for sustaining oscillations independently of the electron tube oscillator system and preventing reactionary effects upon the piezo electric crystal element for stabilizing the operation of the oscillation system.

Another object of my invention is to provide a circuit arrangement for a piezo electric crystal oscillator system in which the effects of the circuit oscillations with respect to the piezo electric crystal element may be reduced to a minimum and high frequency oscillations sustained with a high degree of stability.

Other and further objects of my invention reside in the circuit arrangement of the piezo electric crystal oscillator system as more fully set forth in the specification hereinafter following by reference to the accompanying drawings in which:

Figure 1 illustrates one form of circuit arrangement of the piezo electric crystal oscillator system of my invention; Fig. 2 illustrates a modified form of the piezo electric crystal oscillator system of my invention. In sustaining the oscillations of the piezo electric crystal elements by means of an electron tube oscillator circuit, the inherent oscillations existent in the electron tube system by virtue of the coupling between the circuits of the electron tube have a tendency to react with the oscillations generated by the piezo electric crystal element, thus interfering with the stability of the piezo electric crystal controlled circuits and causing a shift in the frequency of the oscillations which may be developed in the circuits. In the circuit arrangement of my invention I separate the piezo electric crystal generator from a load branch to which the oscillations may be transferred. The oscillations in the load branch

are thus removed from the oscillation generator in such manner that reactionary effects upon the piezo electric crystal element are substantially reduced and interference between the load branch and the oscillation generation circuit substantially eliminated.

Referring to the drawings in detail reference character 1 designates an electron tube arranged in a circuit for sustaining the oscillations of a piezo electric crystal element. Reference character 2 designates an electron tube which is arranged in a branch circuit with respect to the electron tube 1 for control of the oscillations generated in the circuits of electron tube 1 without reactionary effects of the oscillations upon the piezo electric crystal system. The electron tube 1 includes cathode 1a, grid electrode 1b and plate electrode 1c. The electron tube 2 includes cathode 2a, grid electrode 2b and plate electrode 2c. The cathodes 1a and 2a are heated from a power source designated at 3. The output circuits for each of the tubes include a source of potential 4. The electron tube 1 is represented as having an input circuit 5 and an output circuit 6. The input circuit 5 includes a biasing battery 8 and a controlling resistor 7. The output circuit 6 includes a parallel branch circuit 9 consisting of inductance 11 shunted by tuning condenser 10. The piezo electric crystal element which controls the circuits of electron tube 1 is designated at 12 positioned between electrodes 14 and 15. The electrode 14 may be connected with the plate electrode 1c as represented in Fig. 1, while the electrode 15 is connected with the grid electrode 1b whereby constant frequency currents existent across the piezo electric crystal element 12 are impressed upon the circuits of the electron tube 1. The electron tube 2 has its input terminals, that is grid electrode 2b and filament electrode 2a, connected in shunt with the input terminals of the electron tube 1. The output circuit of electron tube 2 is completed from plate electrode 2c through the primary winding of transformer system 20 to high potential source 4 back to the cathode circuit. Inasmuch as grid electrodes 1b and 2b are connected together any variations existent on grid 1b would also exist on grid 100

2b and would be greatly amplified in the output branch of the electrode tube 2.

In Fig. 2 I have shown a switching system 16 having contact 16a and 16b by which the piezo electric crystal element 12 may be connected selectively across the input electrodes or across the grid and the anode of tube 1. I have found that the starting of oscillations may be facilitated in the electron tube circuits when the piezo electric crystal is connectable at will, either across the grid and filament electrodes or across the plate and filament electrodes. I have designated tube 2 having its grid electrode 2b capacitively connected with the grid electrode 1b through the capacity coupling device 17. In order to control the operation of electron tube 2 the input circuit thereof may be bridged by the biasing battery 19 and the control resistor 18. The transformer system 20 conveys the oscillations from the load branch to any desired work circuit.

The load branch constituted by electron tube 2 has its input circuit in common with the input circuit of electron tube 1, and the same source of power is used for heating the cathode and impressing the proper operating potential upon the anode as exists in the circuits of electron tube 1. By separating the load branch from the oscillation generation circuit variations which might exist in the load branch would not necessarily affect the operation of the oscillator circuit. For example, a change in the electron tube 2 would have substantially no effect upon the frequency of oscillations developed in the circuits of electron tube 1. However, such a change occurring in the circuits of the electron tube 1 would substantially shift the frequency. The oscillations which are sustained by the piezo electric crystal element 12 are therefore transferred to the load circuit including electron tube 2 in such manner that reactionary effects upon the piezo electric crystal element 12 are substantially prevented. By reason of the separation of the oscillation generation circuit from the load circuit a high degree of stability in operation of the oscillation circuit is obtained and the effects of variations in the load prevent it from influencing the character of the oscillations in the high frequency generator circuit.

My invention has been found to be highly practical and efficient in operation, and while I have described the circuit arrangements of my invention in preferred embodiments, I desire that it be understood that modifications may be made and that no limitations upon my invention are intended other than are imposed by the scope of the appended claims.

What I claim as new and desire to secure by Letters Patent of the United States is as follows:

1. A piezo electric crystal control system, 65 comprising an electron tube having grid,

cathode and plate electrodes, input and output circuits interconnecting said electrodes, a piezo electric crystal element, switching means for connecting said piezo electric crystal element across said grid and cathode electrodes or across said grid and plate electrodes, said circuits being arranged to sustain the oscillations of said piezo electric crystal element, an auxiliary electron tube system and means connecting the input circuit of said auxiliary electron tube system with the input circuit of said first mentioned electron tube for transferring oscillations sustained by the piezo electric crystal in the circuit of said first mentioned electron tube to the circuit of said last mentioned electron tube and means connected across the input circuit of said last mentioned electron tube for selectively fixing the operating potential of the grid electrode thereof.

2. A piezo electric crystal control system, comprising an electron tube having grid, cathode and plate electrodes, input and output circuits interconnecting said electrodes, a piezo electric crystal element, means connecting said piezo electric crystal element in shunt with said grid and cathode electrodes or in shunt with said grid and plate electrodes, said circuits being arranged for sustaining the oscillations of said piezo electric crystal element, an independent electron tube system having its input circuit connected in parallel with the input circuit of said first mentioned electron tube and independent circuits connected in shunt with each of said input circuits for fixing the operating potential of the grid electrodes of each of said electron tubes whereby the oscillations of said piezo electric crystal element may be transferred to said independent electron tube system while preventing reactionary effects of the oscillations in said independent electron tube system upon said piezo electric crystal element.

3. A piezo electric crystal control system, comprising an electron tube having grid, cathode and plate electrodes, input and output circuits interconnecting said electrodes, a piezo electric crystal element, means for connecting said piezo electric crystal element in shunt with said grid and plate electrodes or in shunt with said grid and cathode electrodes, said circuits being arranged for sustaining oscillations corresponding in frequency to the oscillations of said piezo electric crystal element, an independent electron tube system including input and output circuits with the input circuit of said independent electron tube system connected in parallel with the input circuit of said first mentioned electron tube, separate sources of potential having their negative terminals connected to the grid electrodes of each of said electron tubes for adjusting the operating potential thereof said electron tube sys-

tem operating to sustain the oscillations of said piezo electric crystal element while preventing reactionary effects of said oscillations upon said piezo electric crystal element.

4. A piezo electric crystal control system, comprising an electron tube having grid, cathode and plate electrodes, input and output circuits interconnecting said electrodes, a piezo electric crystal element connected with said circuits, said circuits operating to sustain oscillations corresponding in frequency to oscillations of said piezo electric element, an independent electron tube system including grid, cathode and plate electrodes with the grid electrode connected with the grid electrode of said first mentioned electron tube and cathode electrode thereof connected with the cathode electrode of said first mentioned electron tube and separate circuits including a biasing battery and a variable resistor bridging each of said input circuits for regulating the operating potential of the grid electrodes of each of said tubes whereby oscillations developed by said piezo electric element may be transferred to said electron tube system and the reactionary effects of the oscillations upon said circuits substantially eliminated.

In testimony whereof I affix my signature.
